HINGE

Joseph J. Glanz, New Haven, Conn., assignor to
Aircraft Tools, West Haven, Conn., a partnership

Application August 7, 1945, Serial No. 609,436

11 Claims. (Cl. 16—50)

1

This invention relates to improvements in hinges.

One object of this invention is to provide an improved hinge in which check-means is located behind one of the leaves of such hinge.

Another object of the present invention is to provide an improved hinge in which check-means is located behind one leaf of a hinge, and spring-means is located behind the other leaf of such hinge.

Another object of this invention is to provide an improved hinge in which improved spring-means is located behind one of the leaves of such hinge.

Another object of this invention is to provide improved hinge-means formed of simple elements readily manufactured and readily assembled to produce an efficient and durable construction.

With the above and other objects in view, as will appear to those skilled in the art from the present disclosure, this invention includes all features in the said disclosure which are novel over the prior art.

In the description and claims, the various parts and steps are identified by specific terms for convenience, but they are intended to be as generic in their application as the prior art will permit.

In the accompanying drawings forming part of the present disclosure, in which certain ways of carrying out the invention are shown for illustrative purposes:

Fig. 1 is a front elevation, with part thereof in section on line 1—1 of Fig. 4, of a hinge made in accordance with the present invention;

Fig. 2 is a sectional view on line 2—2 of Fig. 1;

Fig. 3 is a view similar to Fig. 2 but with the hinge opened;

Fig. 4 is a left-end view of Fig. 1;

Fig. 5 is a view on line 5—5 of Fig. 1;

Fig. 6 is a face view of one of the hinge-leaves, alone;

Fig. 7 is a face view of the other hinge-leaf, alone;

Fig. 8 is a view similar to Fig. 1, of the right-hand end of Fig. 1 modified to provide different type spring-means; and

Fig. 9 is a right-end view of Fig. 8.

Referring to Figs. 1 to 7 inclusive of the drawings showing the particular form of the invention chosen for illustration therein, the hinge or hinge-structure 10 is of the concealed type and includes two hinge-leaves or hinge-members 11 and 12 hinged together by means of five links and three hinge-pins or pivot-pins. Two links 13 and

14 are pivoted to the leaf 11 by means of hinge-pin or pivot-pin 15, which links 13 and 14 are, in turn, pivoted to three links 16, 17 and 18 by means of hinge-pin or pivot-pin 19, which links 16, 17 and 18 are, in turn, pivoted to the other leaf 12 by means of hinge-pin or pivot-pin 20. The leaf 11 has two slots 21 (Fig. 6), each having opposite flat parallel sides 22 which neatly slidably fit against the opposite parallel flat sides 10 of the links 13 and 14 adjacent their pivoted connections with the leaf 11.

The leaf 11 also has a guideway 24 provided with two opposite guide-slots 25 and two opposite guide-faces 26. The end of the guideway 15 remote from and behind face 27 of the leaf 11 is closed by a plate 28 (Fig. 1) secured to the leaf 11 by any suitable means as, for example, by the screws 29. The plate 28 has two holes 30 therethrough, each of which is surrounded by an annular spring-centering boss 31. The links 16, 17 and 18 are pivotally connected by a pivot-pin 32 to the two heads 33 of two bolts 34 which extend through the holes 30 of the plate 28, and extend through holes 35 in another plate 36 having annular spring-centering bosses 37 surrounding the holes 35, with a coil-spring 38 on each bolt 34 in centered relation by the bosses 31 and 37 and with nuts 39 threaded on the outer ends of the bolts 34. The opposite ends of the pivot-pin 32 are slidably guided in the guide-slots 25. The flat parallel sides of the links 16, 17 and 18 and of the bolt-heads 33 neatly slidably fill the space between the opposed side guide-walls 26 of the guideway 24 of the leaf 11.

35 The leaf 12 has a slot 40 whose opposite parallel faces 41 neatly slidably fit against the opposite parallel side faces of the link 17 which is pivoted in the slot 40 to the leaf 12, and has two slots 42 each of whose opposite parallel faces 43 40 neatly slidably fit against the opposite parallel side faces of the links 16 and 18 which are pivoted in the slots 42 to the leaf 12. The leaf 12 also has a guideway 44 provided with two opposite guide-slots 45, and opposite guide-faces 46.

45 The links 13 and 14 are pivotally connected by means of a pivot-pin 47 to the head 48 of a bolt or screw 49. The opposite flat parallel side faces of the links 13 and 14 and of the head 48 neatly slidably fit between the two opposed side guide-faces 46 of the guideway 44, and the opposite ends of the pivot-pin 47 are slidably guided in the guide-slots 45.

A check or door check 50 which acts in the manner of dash-pot type door-checks employing a liquid to controllably resist the closing action of

the springs 38, includes a block 51 which is removably secured to the end of the leaf 12 remote from and behind face 52 in any suitable way as, for example, by means of the two socket-head cap-screws 53.

The block 51 is provided with a cylinder or cylindrical bore 54 in which slidably fits a piston 55 carried or formed on the end of a piston-rod 56 which has a threaded axial hole 57 by which it is screw-threadedly connected to the screw-threaded end 58 of the bolt 49 which has its head 48 pivoted to the pivot-pin 47. The piston-rod 56 extends slidably through a soft compressible washer 59 which may, for example, be of neoprene, and which is held compressed between a metal washer 60 and a metal guide-nut 61 so that the washer 59 makes a liquid-tight sliding-fit joint around the outer cylindrical surface of the piston-rod 56. The cylindrical bore 54 of the block 51 is provided with a tapered V-shape groove 62, and a groove 63, for purposes to be hereinafter explained. The piston 55 is provided with a central bore 64 at one end, of a diameter to slidably receive a valve-ball 65, and has a reduced bore 66 leading inwardly from the bore 64 and connecting with two angular passages or holes 67 opening into the annular space 68 behind the piston 55. A conical valve-seat 69 at the inner or rear end of the bore 64 permits the ball 65 to close the passage through the holes 66 and 67. Two slots 70 at right angles to each other, provide means for rapid passage of liquid from the annular space 68 behind the piston 55, through the passages 67, 66 and 64 when the ball 65 is off of its seat 69. The ball 65 is held from coming out of the bore 64 by means of end portions 71 of the end of the piston 55 adjacent the front end of the bore 64 being peened over sufficiently to prevent the ball 65 from coming completely out of the bore 64, and yet permitting a small amount of longitudinal movement of the ball in accomplishing its valve-closing and -opening actions.

The space 72 is front of the piston 55 is connected by means of passages 73, 74 and 75 to the annular space 68 at the rear of the piston 55. The right-hand end (Fig. 1) of the passage 74 is provided with a conical valve-seat 76 against which seats a conical end 77 of a socket-head leakage-control or needle-valve screw 78 which is threadedly adjustable through a guide-nut 79 which holds a washer 80 of compressible material such, for example, as neoprene, compressed in fluid-tight engagement with the screw 78. A hexagon socket 81 in the screw 78 is available for adjustment through the front face 52 of the leaf 12 (Fig. 5).

The piston 55 is preferably given a fit sufficiently close with the bore 54 to not provide sufficient leakage past the piston to permit proper closure of the door or other member on which the hinge is employed, and, therefore, additional leakage is provided by proper adjustment of the screw 78 back away from the conical seat 76 to provide just the proper degree of total leakage from the space 72 in front of the piston 55 to the annular space 68 at the rear of the piston to provide proper closing speed for the door. Also, the tapered groove 62 in the cylindrical bore 54 permits a larger amount of leakage of liquid past the piston at the start of the closing movement of the door, and as the piston travels further along the bore 54, it reaches a smaller portion of the tapered groove 62 which thus decreases the leakage, thus increasing the hydraulic

resistance or dash-pot resistance against the closing action of the springs. Finally, when the door has almost reached its closed position corresponding to the positions of the parts illustrated in Fig. 1, the piston 55 will have traveled beyond the rear end 82 of the groove 63 to thus cause a sudden drop in the resistance to the leakage, or, in other words, a sudden increase in leakage, to thereby permit the spring-means to accomplish the final portion of the closing movement of the door. During this closing movement of the door, the piston 55 will move from its position in Fig. 3 to that in Fig. 2 and will thus cause the ball 65 to be forced against its seat 69 by the liquid to thus completely block the passage of liquid through the passages 66 and 67 to the rear of the piston. When the door is swung open from the position of Fig. 2 to Fig. 3, the liquid in the annular space 68 at the rear of the piston 55 will push against the ball 65, moving it out to its outermost position against the peened-over portions 71, to thus permit substantially free unrestricted flow of the liquid from the rear of the piston to the front of the piston, thus not checking or inhibiting the opening action of the door in any substantial degree, the only inhibiting action against the opening of the door being the compressing action which takes place in the springs 38.

In the modified form of the invention illustrated in Figs. 8 and 9, a modification of the spring-means is shown for actuating the hinge. Instead of employing coiled springs such as 38 illustrated in Figs. 1 to 3, three pairs of bowed leaf-springs 83 are mounted on a bolt 84 which extends through a hole 85 in a plate 36a and has its head 86 pivoted to the pivot-pin 32 between the spaced-apart ears 87 of the link 11a, which ears 87 are also pivotally connected to the pivot-pin 32. Cylindrical spacer-sleeves 88 having parallel end or side faces, are mounted on the pivot-pin 32 in place of the heads 33 of the bolts 32 of the form of the invention shown in Fig. 1. A nut 39 is threaded on the end of the bolt 84 to engage against the outermost of the leaf-springs 83. A casing or housing 89 which may be of sheet metal, has an interior width just sufficiently larger than the width of the leaf-springs 83 to permit them to slide freely during their spring-action movements, thus facilitating holding the leaf-springs 83 in aligned position. The casing 89 may be connected to plate 36a in any suitable way as, for example, by spot-welding or brazing it thereto, or by making it integral therewith.

In employing hinge-means or constructions in accordance with the present invention such, for example, as the hinge shown in Fig. 1, on a door, a recess would be made in the rear edge of the door, of sufficient size and depth to accommodate the leaf 12 together with the check 50, with the face or front face 52 of the leaf 12 at or below the plane of the rear edge of the door. And the leaf 11, together with the springs 38 and related parts, would be mounted in a recess made in the casing at the rear edge of the door, with the face or front face 27 of the leaf 11 at or below the plane of the edge-face of the casing at the rear edge of the door, the two leaves 11 and 12 being hinged together as hereinbefore fully explained. The leaves 11 and 12 would be secured to the door and door-casing in a way well known to those skilled in the art, by screws or bolts engaging in the countersunk holes 90 of the leaves of the hinge.

Assuming the door to be in closed position, in

which the hinge would be in the position illustrated in Figs. 1 and 2, if now the door is swung open to a right-angle position such as illustrated in Fig. 3, the springs 38 will be compressed as illustrated in Fig. 3, and as the piston 55 moves from its position shown in Figs. 1 and 2 to that shown in Fig. 3, the ball 65 will be pushed off its seat by the liquid which rushes without substantial resistance from the annular space 68 behind the piston 55 through the passages 67, 66 and 64 into the space 72 in front of the piston 55, without producing substantially any checking or resisting action to the opening of the door, the only resistance being the compressing action against the springs 38. If now the door is permitted to swing shut, the springs 38 in their effort to move from their compressed position illustrated in Fig. 3 to their expanded position illustrated in Figs. 1 and 2, start to swing the door from the position illustrated in Fig. 3 to that illustrated in Figs. 1 and 2. At the start of this movement, the tapered groove 62 permits an ample but gradually-decreasing amount of leakage of the fluid from the space 72 in front of the piston 55 to the space 68 behind the piston, so that at the very start of the closing movement of the door little or no checking action occurs, but later on, a gradual increasing degree of checking action occurs until the piston moves sufficiently far beyond its position illustrated in Fig. 3, when maximum checking action occurs due to the fact that here is only a small leakage past the outer cylindrical surface of the piston, and such additional leakage as is purposely permitted by the needle-valve screw 73. Finally, after the door has been slowly swung through most of its final movement by the expanding action of the springs 38, the piston 55 reaches a location where its rear edge passes beyond the rear end 82 of the groove 63, whereupon a sudden increase of leakage from the space 72 in front of the piston 55 to the space 68 behind the piston occurs in such amount as to substantially eliminate or greatly reduce the checking action, whereupon the expansion of the springs 38 produces the final closing movement of the door. And of course it will be evident that the action will be essentially the same, whether the construction employs the coil springs illustrated in Figs. 1, 2 and 3, or the leaf springs illustrated in Figs. 8 and 9.

While each hinge of a door could employ both the spring action and the check action after the manner illustrated in Figs. 1, 2 and 3, it will be appreciated that where a door has two or three or more hinges, one or more of such hinges could have both the spring action and the check action, and one or more of the others could have the spring action only or the check action only. Or one or more of the hinges could have a spring action only, and one or more of the other hinges could have the check action only. These different constructions could be readily provided by modifying the construction illustrated in Figs. 1, 2 and 3 by, for example, leaving off the springs, or by leaving off the check. If in leaving off the springs it is desired to also omit all their associated parts such as the bolts 34, then upon removal of the bolts, spacer-collars such as 88 of Fig. 8, of the same width and having parallel faces similar to the heads 33 of the bolts 34 would be substituted in place of the latter upon the pivot-pin 32. Similarly, if the bolt 49 of the check were to be removed along with the check, then a similar spacer-collar of the same width and with par-

allel faces corresponding to the head 48 of the bolt 49 would be substituted for the latter upon the pivot-pin 47.

Ordinarily, it is easy to get all the checking action needed for an ordinary door by employing a single check, and therefore it would ordinarily only be necessary to employ one check along with springs on one hinge of a door, and the other hinge or the other two hinges of the door could have the spring action only, without any check.

Regardless of the constantly changing angular positions of the links 16, 17, 18, 13 and 14 during the opening and closing movements of the hinge, the guide-slots 25 and 45 ensure that the axis of the pivot-pin 32 which is pulled by the bolt-heads 33, will travel in a plane containing the axes of the bolts 34, and that the axis of the pivot-pin 47 which pushes the head 48 of the bolt 49, will travel in a plane containing the axis of the bolt 49 and the piston-rod 56. It will also be observed that as the links 16, 17 and 18 and the bolt-heads 33 (or spacer-sleeves when they are employed) all have parallel sides neatly and slidably fitting between the two opposed parallel surfaces 26 of the guideway 24 of the leaf 11, that great strength and perfection of action of the hinge in resisting the downward pulling stress due to the weight of the door, is accomplished. In a similar manner, the links 13 and 14 and the bolt-head 48 neatly and slidably fit between the opposed parallel faces 46 of the guideway 44 of the leaf 12 to thus effectively resist the downward stress due to the weight of the door.

Where first and second hinge-leaves or other parts are referred to in the claims, there is no significance to the words "first" and "second" other than for purposes of identification as between two similar parts.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. Hinge-means including: a pair of hinge-leaves each having a face, and said leaves hinged together to provide hinging-movement toward and from a closed position; spring-means adapted to move said leaves toward said closed position; and check-means located between the top and bottom and behind said face of, and supported by one of said leaves and employing liquid actuated by a piston having a direction of movement substantially at right angles to said face of the leaf, by which leaf said check-means is supported, and adapted to controllably resist the closing-action of said spring-means.

2. Hinge-means including: a pair of first and second hinge-leaves each having a face, and said leaves hinged together to provide hinging-movement toward and from a closed position; a spring-means adapted to move said leaves toward said closed position; check-means located behind said face of said second leaf; link-means connected to said first leaf and having an operating-portion movable in opposite directions transversely of and behind said face of said second leaf; connecting-rod means connected to said check-means and having a pivot-connection with said operating-portion; said second leaf having guide-means adapted to guide said pivot-connection to

cause its center to move in substantially a straight line; and said check-means and its connections adapted to controllably resist the closing-action of said spring-means.

3. Hinge-means including: a pair of first and second hinge-leaves each having a face, and said leaves hinged together to provide hinging-movement of said leaves toward and from a closed position; spring-means located behind said face of said first leaf; first link-means connected to said second leaf and having a first operating-portion movable in opposite directions transversely of and behind said face of said first leaf; first connecting-rod means connected to said spring-means and having a first pivot-connection with said first operating-portion; said first leaf having guide-means adapted to guide said first pivot-connection to cause its center to move in substantially a straight line; check-means located behind said face of said second leaf; second link-means connected to said first leaf and having a second operating-portion movable in opposite directions transversely of and behind said face of said second leaf; second connecting-rod means connected to said check-means and having a second pivot-connection with said second operating-portion; said second leaf having guide-means adapted to guide said second pivot-connection to cause its center to move in substantially a straight line.

4. Hinge-means including: a pair of first and second hinge-leaves each having a face, and said leaves hinged together to provide hinging-movement of said leaves toward and from a closed position; spring-means comprising a plurality of side-by-side coil-springs located behind said face of said first leaf; first link-means connected to said second leaf and having a first operating-portion movable in opposite directions transversely of and behind said face of said first leaf; first connecting-rod means connected to said spring-means and having a first pivot-connection with said first operating-portion; said first leaf having guide-means adapted to guide said first pivot-connection to cause its center to move in substantially a straight line; check-means located behind said face of said second leaf; second link-means connected to said first leaf and having a second operating-portion movable in opposite directions transversely of and behind said face of said second leaf; second connecting-rod means connected to said check-means and having a second pivot-connection with said second operating-portion; said second leaf having guide-means adapted to guide said second pivot-connection to cause its center to move in substantially a straight line.

5. Hinge-means including: a pair of first and second hinge-leaves each having a face, and said leaves hinged together to provide hinging-movement of said leaves toward and from a closed position; spring-means comprising bowed leaf-spring means located behind said face of said first leaf; first link-means connected to said second leaf and having a first operating-portion movable in opposite directions transversely of and behind said face of said first leaf; first connecting-rod means connected to said spring-means and having a first pivot-connection with said first operating-portion; said first leaf having guide-means adapted to guide said first pivot-connection to cause its center to move in substantially a straight line; check-means located behind said face of said second leaf; second link-means connected to said first leaf and having a second operating-portion movable in opposite directions

transversely of and behind said face of said second leaf; second connecting-rod means connected to said check-means and having a second pivot-connection with said second operating-portion; said second leaf having guide-means adapted to guide said second pivot-connection to cause its center to move in substantially a straight line.

6. Hinge-means including: a pair of first and second hinge-leaves each having a face, and said leaves hinged together to provide hinging-movement toward and from a closed position; spring-means located behind said face of said first leaf; link-means connected to said second leaf and having an operating-portion movable in opposite directions transversely of and behind said face of said first leaf; connecting-rod means connected to said spring-means and having a pivot-connection with said operating-portion; said first leaf having guide-means adapted to guide said pivot-connection to cause its center to move in substantially a straight line; and said spring-means and its connections adapted to move said leaves toward said closed position.

7. Hinge-means including: a pair of first and second hinge-leaves each having a face, and said leaves hinged together to provide hinging-movement toward and from a closed position; spring-means comprising a plurality of side-by-side coil-springs located behind said face of said first leaf; link-means connected to said second leaf and having an operating-portion movable in opposite directions transversely of and behind said face of said first leaf; connecting-rod means connected to said spring-means and having a pivot-connection with said operating-portion; said first leaf having guide-means adapted to guide said pivot-connection to cause its center to move in substantially a straight line; and said spring-means and its connections adapted to move said leaves toward said closed position.

8. Hinge-means including: a pair of first and second hinge-leaves each having a face, and said leaves hinged together to provide hinging-movement toward and from a closed position; spring-means comprising bowed leaf-spring means located behind said face of said first leaf; link-means connected to said second leaf and having an operating-portion movable in opposite directions transversely of and behind said face of said first leaf; connecting-rod means connected to said spring-means and having a pivot-connection with said operating-portion; said first leaf having guide-means adapted to guide said pivot-connection to cause its center to move in substantially a straight line; and said spring-means and its connections adapted to move said leaves toward said closed position.

9. Hinge-means including: a pair of hinge-leaves each having a face, and said leaves hinged together to provide hinging-movement toward and from a closed position; and check-means located between the top and bottom and behind said face of, and supported by one of said leaves and employing liquid actuated by a piston having a direction of movement substantially at right angles to said face of the leaf, by which leaf said check-means is supported, and adapted to controllably resist closing-movement of said hinge-means.

10. Hinge-means including: a pair of first and second hinge-leaves each having a face, and said leaves hinged together to provide hinging-movement toward and from a closed position; check-means located between the top and bottom and behind said face of, and supported by said sec-

ond leaf and employing liquid actuated by a piston having a direction of movement substantially at right angles to said face of the leaf, by which leaf said check-means is supported, and adapted to controllably resist closing-movement of said hinge-means; said check-means including adjustable leakage-control valve-means for said liquid, and adjusting-means for said valve-means adjustable by means of an opening through said face of said second leaf.

11. Hinge-means including: a pair of first and second hinge-leaves each having a face, and said leaves hinged together to provide hinging-movement toward and from a closed position; check-means located behind said face of said second leaf; link-means connected to said first leaf and having an operating-portion movable in opposite directions transversely of and behind said face of said second leaf; connecting-rod means connect-

ed to said check-means and having a pivot-connection with said operating-portion; said second leaf having guide-means adapted to guide said pivot-connection to cause its center to move in substantially a straight line; and said check-means and its connections adapted to controllably resist closing-movement of said hinge-means.

JOSEPH J. GLANZ.
